UNITED STATES PATENT OFFICE.

ISIDOR KITSEE, OF PHILADELPHIA, PENNSYLVANIA.

PRODUCING INTEGRAL MULTICOLORED SCREENS ON PHOTOGRAPHIC BLANKS.

Original application filed April 27, 1921, Serial No. 464,789. Divided and this application filed December 7, 1921. Serial No. 520,683.

To all whom it may concern:

Be it known that I, ISIDOR KITSEE, citizen of the United States, residing at Philadelphia, in the county of Philadelphia and 5 State of Pennsylvania, have invented certain new and useful Improvements in Producing Integral Multicolored Screens on Photographic Blanks (Division "B" of application Serial No. 464,789, filed April 27, 1921), 10 of which the following is a specification.

My invention relates to an improvement in producing integral multi-colored screens on photographic blanks.

This application is a division (called 15 Division B) of application Serial No. 464,789, filed April 27, 1921.

My invention embraces not only the process with the aid of which a celluloid or like blank may be provided with configurations of different colors, but it also contemplates the means and method of applying these configurations in a simple and economical manner to the photographic blank. I am well aware that attempts have been made 20 to produce multi-colored screens integral with photographic blanks. I am also aware that Letters Patents in the United States and other countries have been issued for multi-colored screens, but so far no multi-colored screens integral with photographic blanks, useful for moving picture work have been made commercially, and none of the Letters Patents described the means, so 25 that persons versed in the art can produce such screens on commercial basis.

It is one thing, to state that configurations of two or more colors should be produced in required minuteness on a photographic blank, but it is of far greater importance 40 to clearly point-out not only the different steps required, but also the different parts of the apparatus to be used in constructing such screens, so that persons versed in the art may successfully produce the same in 45 commercial quantities.

I will first describe the process or method, with the aid of which a multi-colored screen can be produced directly on a celluloid or other suitable blank. As my invention has 50 more special reference to moving picture films I take it for granted that the photographic blank consists of the usual celluloid film.

In the accompanying drawing, which 55 illustrates one form my invention may take,

Figs. 1 to 6 inclusive are plan views of parts of a film representing different stages in the course of producing the multi-colored screens thereon. Fig. 7 is a vertical longitudinal section partly in elevation of the device used in the production of the integral color screen. Fig. 8 is a vertical transverse section taken on the line 8—8 of Fig. 7. Fig. 9 is a plan view of two adjacent discs out of which the roller as illustrated in 60 Fig. 8 is produced and of which the discs of Fig. 7 are parts. Fig. 10 is a plan view of one of the discs similar to those of Fig. 9, but with the part not recessed provided with teeth. Fig. 11 is a plan view of 65 another modified form of disc, the disc comprising a number of recessed parts interspersed by parts not recessed.

In Figs. 1 to 6, 1 is the celluloid base, 2 the color with which one surface of the 70 celluloid is tinted, and as I have selected here the screen to consist of the two colors, green and red, the color 2 represents here, green. 3 indicates a covering layer, surfacing the green tinted celluloid. 4 indicates 75 the spaces from which the covering layer and the green tint have been removed, 5 indicates the formerly clear spaces tinted now with a second color, here red. In Fig. 6 the whole screen is indicated by 6 and consists 80 here of red lines interspersed by green lines the covering layer being entirely removed. It will be noted that the lines—red as well as green—do not extend the entire length of 85 of the film, but that the lines, the red as well as the green are broken up and interspersed longitudinally as well as transversely, the red and the green lines alternating 90 each other in both directions. These alternations are produced through special arrangement of the discs as will later on, in 95 describing these discs, be more clearly set forth. In Figs. 7 and 8 the device consists of a race-track 8, in its broad construction similar to the construction of the race-track 100 in moving picture projectors and provided with means 9—9 to adjust the same, so that the film passing through the race-track may be provided with the required pressure to hold the same in level position. 10 indicates 105 a series of discs comprising the discs 11 and the discs 12, the discs 12 being positioned alternately between the discs 11. Each of the discs, 11 as well as 12, is so constructed 110 that only part of same, here one-half of its

2

circumference will in the working of the device come in cutting contact with the underlying film and for this reason each of the discs comprises the cutout part or clearance 24, designed not to contact with the film and the part indicated by 25, which in the working of the device comes in cutting contact with the film, whereby it will remove that part of the protective coating 10 and color layer with which the film is provided, but it has to be noted, that in the assembled roller the discs are assembled in a manner, so that the cutout part of one disc is opposite to the cutout part of the 15 adjacent disc. In other words, when the discs are assembled on the shaft they will form or present a roller consisting of a series of discs, one-half of the circumference of each disc recessed, but the recessed halves 20 of the adjoining discs oppositely positioned, as is clearly illustrated in Fig. 9, so that in the working of the device, that is during each revolution of the roller, only one-half of the discs will be active as cutting discs 25 during one-half of the revolution of the roller and the other half of the discs will only be active as cutting discs during the second half of the revolution. The whole series of discs is positioned on and keyed 30 to the revolvable shaft 13. 14—14 are means to hold the discs together in tight assembly. 15 are the means to raise and lower and place in exact relation the whole series of discs as to the film 16 passing through the 35 race-track. In practice, I have found that the multi-colored screen does not need to have colored lines thereon of a smaller width than about 1-500 of an inch for each line. The screen therefore will consist here of 40 green lines of about 1-500 of an inch in width interspaced, transversely as well as longitudinally, by red lines approximately the same width. Taking now for granted that the screen will consist, transversely 45 considered of 500 lines per inch, 250 of each color, and taking for granted that the screen will be produced with the aid of the device as illustrated in Figs. 7 and 8, it has to be stated, that each of the discs, 11 50 as well as 12 should be about 1-500 of an inch in thickness. For better understanding I call the whole series of discs, as assembled on the shaft, the cutting roller and each inch of this cutting roller will therefore consist of 500 discs, 250 of which are 55 recessed as to one half of their circumference in respect to one position of the roller and 250 of which are recessed as to one half of their circumference in respect to the opposite position of the roller. In practice, I have found that a very convenient size for these discs is from 2 to 3 inches in diameter. 17 is an adjustable free revolving roller, positioned in the cutout place 60 65 26 of the race-track and adapted to contact with the film 16, so that the same may not deviate from its proper position. 18 is an electric motor, with the aid of which the cutting roller may be revolved. I have here shown the motor as being connected to the shaft 13 with the aid of a belt 27. The reason for this is: If the motor be connected directly to the shaft, the vibrations of the motor may injuriously affect the operation of the cutting roller. 19 is a spool from which the film is unwound during operation, 20 the film already acted upon by the cutting roller and 21 is the means to draw the film under the cutting 70 75 80 85 90 95 100 105 110 115 120 125 130 roller.

The mode or method of producing the multi-colored screen according to my invention is substantially as follows: As my invention has more special reference to moving picture films, I will refer to the celluloid blank as film or part of film, useful to take thereon, after completion of the process and proper coating with pan-chromatic emulsion, negatives with the aid of which, positives may be produced and exhibited in the same manner and with substantially the same apparatus as moving pictures are projected today.

The first requisite is, a celluloid blank in the form of a film, either perforated or unperforated. This film is then tinted on one surface with one color. The tinting with the color may be produced with the aid of rollers or brushes, and in this case, the opposite surface does not require any protective coating. The dye-solution should be such as to affect the celluloid proper, but in a very mild degree. For this purpose dyes have to be selected, soluble in alcohol, and an agent affecting the celluloid has to be added. This agent may consist of any of the usual solvents, such for instance as amylacetate, acetone or ether. In the practical working, it was found, that a very even tint can be applied to the celluloid, if the film is immersed in the liquid and moved to and fro. But in this case the underside or opposite surface has to be protected from the action of the dye-solution. This can readily be accomplished by covering the underside with a light coating of gelatine or gum arabic. Care shall be taken not to make the dye-solution too active or to leave the film too long in this solution, as otherwise the tinting will penetrate to a depth greater than desired. After the film is taken from the color bath, the same is subjected to a drying process either with or without the aid of artificial means. When completely dry, the tinted surface is provided with a protective layer, such for instance as was used for protecting the underside from the dye-solution, that is with a coating of gelatine, gum arabic or substance similar in action. After drying the film

is subjected to a cutting process with the aid of the device, substantially as is illustrated in Figs. 7, 8 and 9, in the following manner: The film is wound around a spool 5 and the free end of the film is threaded or carried through the race-track of the device and this end is then carried through the pulling means, here 21. This means is adapted to be rotated with the aid of an 10 electric motor or device similar in action. In practice I prefer an electric motor as its speed can easily be regulated with the aid of a variable rheostat. The cutting roller has to be adjusted then in a manner so that the 15 discs at the true or unrecessed diameter should slightly press on the film and should, when rotated cut through the protecting layer and that part of the surface of the film which is tinted, so that the protective layer 20 as well as the tinted surface is removed and a space freed from the color and protective coating is produced. In practice it has been found that the greater the rotating speed of the cutting roller, the greater the 25 efficiency of same. For all practical purposes it is suggested, that the speed of the cutting roller should be about double or greater than the speed of the moving film, 1800 to 2500 revolutions per minute of the 30 cutting roller is not excessive. This speed can be regulated by the sizes of the pulleys on the shaft of the cutting roller and on the shaft of the motor respectively. The movement of the film should be in a direction opposite to the direction of the revolving cutting roller, as is clearly indicated by the different arrows; the feathered arrow indicating the direction of rotation of the cutting roller and the unfeathered arrow the 35 direction of the movement of the film through the race-track. After the whole length of the film has passed through the race-track and has been acted upon by the cutting roller, it will present an appearance 40 substantially as follows: colored lines of comparatively short length interspaced transversely and longitudinally by short lines minus the color and the protective layer. In other words the film will 45 represent a surface in which short colored lines will alternate transversely and longitudinally with short clear lines. A film of this description is clearly illustrated in 50 Fig. 4.

55 The upper surface of the film so produced is then subjected to a dye-solution of a color different from that of the first dye-solution, but this solution should have substantially the same properties as the first 60 dye-solution. It should effectually tint the celluloid now laid bare through the cutting off of the protective layer and formerly tinted part of the celluloid. It has to be stated, that if the laying on of the second 65 color is produced with the aid of rollers

or brushes, it is unnecessary to give the underside a protective coating; but, as it has been found in practice, that the immersion of the whole film in the dye-solution is the more practical and efficient, then the 70 underside has to be provided with a protective layer similar to the protective layer above referred to. Care has to be taken that the individual cutters or discs should be of exactly the same diameter, 75 so that no disc should protrude or be recessed as compared with the other discs, as otherwise the finished product will not be satisfactory. Care should also be taken to place the cutting roller in exact position as 80 to the surface of the film to be cut and therefore the adjustment as indicated by 15 in Figs. 7 and 8 should be micrometrically correct. The film, after the second tinting will, if green and red are used as 85 dyeing solutions, represent a surface substantially as illustrated in Fig. 5. The remaining protective coating may then be removed by simply washing the film in water and the film will present a surface 90 substantially as illustrated in Fig. 6.

To reduce the heat, generated through the friction of the cutting roller and the moving film, means have to be provided to conduct this heat from the device and a blast of 95 cool air, as practice has proven, will effectually reduce the temperature of the cutting roller as well as that of the film. In Fig. 7, 23 indicates part of the means through which the cold air is conveyed onto the cutting roller and the moving film.

In the drawing I have selected to be shown a perforated film as being acted upon by the cutting roller, and therefore the means to draw the film through the race-track is illustrated as the usual sprocket wheels, but if the film be unperforated, suitable friction rollers may be substituted for the sprocket wheels.

During the explanation of the drawing I 110 have given figures of the diameter of the discs, but it is obvious that the diameter of the discs may be increased or decreased in accordance with requirements. I have also pointed out satisfactory speeds of the cutting roller as well as of the moving film; 115 these speeds may be increased or decreased or the relative speeds of the roller and film may be changed in accordance with requirements without departing from the scope of 120 my invention.

I have illustrated the discs to be smooth-edged because I have found this construction of the disc very satisfactory, but if it is desired to make the edges ragged, notched 125 or toothed, results may also be produced from the revolving roller, but care has to be taken that the ragged edges or teeth 28 should not be clogged up or when clogged up, that they be cleaned as otherwise the 130

result will not be satisfactory and the film will present an uneven appearance. I must also add, that if toothed discs be employed, the movement of the film as to the number of revolutions of the discs should be greatly reduced. I have also illustrated and described each cutting disc to comprise one continuous cutting edge, inter-spaced by one continuous recessed space, but it is obvious that each of the discs may comprise a series of shorter cutting edges, inter-spaced by a recessed space.

The attention of persons desiring to practice my invention has to be called to the fact that the length of each of the colored lines will depend to the greatest extent on the ratio of speed between the revolving discs and the moving film. The greater the difference between the two elements; that is the greater the speed of the revolving roller and the slower the speed of the moving film in relation therewith, the shorter will be the transparent lines produced by the cutting of the discs and therefore the shorter will be the colored configurations in the finished film.

Having now described my invention, what I claim as new and desire to secure by Letters Patent is:

- 30 1. A moving picture film provided with comparatively short lines of different colors, both color lines directly on the celluloid proper and one color line recessed as to the adjoining color line.
- 35 2. As a new article of manufacture a moving picture film, comprising the celluloid film proper and, longitudinally and transversely considered, a series of comparatively short lines, the lines of one color alternating with the lines of a second color, the colors embedded in the celluloid proper.

3. A celluloid film useful for moving picture work provided with an integral color screen, the colors embedded in the celluloid and presenting short longitudinal lines of 45 different colors.

4. A celluloid film useful for moving picture work provided with an integral color screen, presenting a mosaic design, parts in intaglio and parts in relief. 50

5. As a new article of commerce a moving picture film provided on its surface with comparatively short lines of one color inter-spaced by comparative short lines of a second color, the lines of one color in intaglio as 55 to the lines of the second color.

6. As a new article of commerce a celluloid blank useful for photography, the surface impregnated with comparative short lines of one color interspaced—longitudinally and 60 transversely considered—by comparative short lines of a second color.

7. A color screen integral with photographic blanks comprising at least two colors and at least one color comprising comparatively short lines, some of the lines in intaglio as to the adjoining lines. 65

8. As a new article of manufacture a moving picture film provided with an integral screen, the screen consisting of comparatively short lines of one color inter-spaced by comparatively short lines of a second color, some of said short lines in intaglio and some in relief. 70

9. A celluloid blank useful for photographic purposes having thereon comparatively short lines of one color longitudinally interspaced by comparatively short lines of a second color, both of said colors embedded in the celluloid proper. 75

In testimony whereof I affix my signature.

ISIDOR KITSEE.
